UNITED STATES PATENT OFFICE.

ORESTES TAGLIAFERRY, OF CINCINNATI, OHIO.

NONSKIDDING DEVICE FOR SHOES.

Application filed May 3, 1920. Serial No. 378,387.

To all whom it may concern:

Be it known that I, ORESTES TAGLIAFERRY, a citizen of the United States, residing in Cincinnati, in the county of Hamilton and 5 State of Ohio, have invented certain new and useful Improvements in Nonskidding Devices for Shoes, of which the following is a specification.

My invention relates particularly to nonskidding devices for shoes to be worn by 10 men, women and children.

The objects of my invention are to provide a thoroughly practical non-skidding device of simple, inexpensive, light, strong and 15 durable construction which is adapted to be easily and conveniently applied to or removed from the shoe and which is efficient in use when walking on snow, ice, sleet, leaves, mud or steep or irregular surfaces; 20 to provide a device of this character, which can be easily and readily adjusted to comfortably fit various sizes of shoes and which can also be folded into compact space for carrying in the pocket or otherwise; to provide 25 such a device which may be adjusted to different positions upon the sole of the shoe, and to provide a device which will permit of perfect freedom of movement of the wearer, as well as preventing slipping without undue strain upon the foot.

My invention consists of a plurality of plates each having a plurality of projections or points extending from its lower surface, said plates being connected together 35 by links or chains and being attached to belts by which the device is fastened upon the sole of a shoe.

My invention also consists in the details of construction and in the parts and combination and arrangement of parts as herein set forth and claimed.

In the drawings:

Fig. 1 is a bottom view of the device partly broken away;

Fig. 2 is a longitudinal section on the line 2—2 of Fig. 1;

Fig. 3 is a side view of a shoe having the device clamped thereon;

Fig. 4 is a side elevation of one of the 50 projections or holding points.

In the embodiment of my invention as illustrated and which shows a preferred construction, I provide a plurality of plates 5, preferably of metal, each having a plurality of holes 6, each hole being adapted to re-

ceive a holding point 7 having its shank 8 fitting snugly in the hole and its end riveted over the top surface of plate 5, so that the flattened end 9 and the shoulder 10 of the holding point 7 will be firmly and securely 60 fastened to plate 5. Holding point 7 is preferably conical so that as the point wears dull, it can be easily and quickly sharpened. Plates 5 are spaced apart and connected by links or chains 11, the links engaging in 65 holes 12 in the edge of each plate. This permits the device to adapt itself to the form of the shoe sole and provides for economy in construction, as less material is thus required. It also permits the holding points 70 7 to more readily adapt themselves to the surface over which the user travels, whereby a firm non-skidding hold is assured at every step.

Each plate is provided with a hole 13 75 near its end to receive rivet 14 for the purpose of securing leather or cloth straps or belts 15 on the upper side at each end of the respective plates, said rivets being extended through said belts with a leather or 80 other washer 16 upon the upper side through which the split end 17 of the rivet extends and has its split or bifurcated ends split apart and riveted down upon the washer to securely hold the plates to the straps or 85 belts. Each strap or belt is provided with a suitable buckle 18 upon one end by which the device is firmly clamped and held upon the shoe sole at any point desired, but I prefer to secure it at or near the ball of the foot 90 so that the device is brought substantially centrally of the sole and held at a point where it will insure holding contact of the shoe to the surface over which the user walks. This device is very compact and of 95 neat construction and appearance and the straps are brought over the vamp at a point below or at the lower end of the lace so that the shoe may be readily opened for putting on or taking off without disturbing the 100 straps or belts 15. My construction, in which the holding points are secured to a plurality of plates flexibly connected together, renders walking easy and comfortable and positively prevents slipping under 105 all circumstances, even where the surface is very rough and uneven.

From the above description, it will be seen that my device can be quickly and easily attached to or detached from a shoe 110

and that when detached from the shoe, it can be folded into a small package for conveniently carrying in the pocket.

It will be seen that my device, which is particularly adapted to be secured to the ball of the foot, greatly facilitates walking without increasing fatigue and insures a positive grip for the foot on slippery surfaces.

10 While I have shown a preferred construction, it will be apparent that my invention is capable of modification without departure from its scope or spirit, and I do not, therefore, restrict myself to the exact details of 15 construction shown and described, but mean

and intend to claim all equivalents and variations thereof, as defined by the following claim:

A non-skidding device for shoes comprising a plurality of plates spaced apart from each other and each having holding points on its lower side, links or chains connecting said plates near each end thereof in flexible relation to each other, a pair of straps attached to the respective ends of said plates and means for detachably connecting the respective ends of each strap together in adjusted relation, substantially as set forth and for the purposes specified.

ORESTES TAGLIAFERRY.
